US00D783282S

(12) **United States Design Patent** (10) **Patent No.:** **US D783,282 S**
(45) **Date of Patent:** **** Apr. 11, 2017**

(54) **LUGGAGE**

(71) Applicant: **Samsonite IP Holdings S.a.r.l.**,
Luxembourg (LU)

(72) Inventor: **Erik Sijmons**, Oudenaarde (BE)

(73) Assignee: **Samsonite IP Holdings S.a.r.l.**,
Luxembourg (LU)

(**) Term: **15 Years**

(21) Appl. No.: **29/538,137**

(22) Filed: **Sep. 1, 2015**

(30) **Foreign Application Priority Data**

Mar. 10, 2015 (EM) 002649558-0001

(51) **LOC (10) Cl.** **03-01**

(52) **U.S. Cl.** **D3/279**
USPC **D3/279**

(58) **Field of Classification Search**

USPC D3/273, 276, 279, 281, 282, 289, 283
CPC A45C 5/00; A45C 5/03; A45C 2005/037;

A45C 5/14; A45C 7/0027; A45C 7/0018

See application file for complete search history.

(57) **CLAIM**

The ornamental design for a luggage, as shown and described.

DESCRIPTION

FIG. 1 shows a front perspective view of the luggage; FIG. 2 shows a front elevation view of the luggage of FIG. 1;

FIG. 3 shows a rear elevation view of the luggage of FIG. 1;

FIG. 4 shows a right elevation view of the luggage of FIG. 1;

FIG. 5 shows a left elevation view of the luggage of FIG. 1; FIG. 6 shows a top view of the luggage of FIG. 1; and, FIG. 7 shows a bottom view of the luggage of FIG. 1.

The broken lines in FIGS. 1-7 illustrate the portions of the luggage and form no part of the claimed invention.

1 Claim, 7 Drawing Sheets
